[57] ABSTRACT

An upright revolving display rack of a type having a plurality of vertically elongated display panels disposed in angularly spaced relation and brought into view by revolving the rack about an upright axis. The rack has a frame structure for mounting the panels and which is foldable to fit in a relatively flat package and the foldable frame structure is short as compared to the vertical height of the panels so that the foldable frame structure can fit into a relatively short package. The panels are divided lengthwise into a pair of separate panel sections to allow the panels to fit in the same relatively short flat package with the foldable frame structure.

UPRIGHT REVOLVING DISPLAY RACK

BACKGROUND OF THE INVENTION

This invention relates to an upright revolvable display rack of the type adapted to stand on the floor and having a plurality of vertically elongated display panels disposed at angularly spaced relationship and brought into view by revolving the rack about an upright axis. In order to facilitate shipment of such racks, it has heretofore been proposed, disclosed in the patent to T. M. Bleed, U.S. Pat. No. 3,092,258, to provide a frame structure for rotatably supporting the display panels in which the frame structure was foldable to a relatively flat condition for reception in a flat package with the display panels. However, such revolvable display racks are relatively tall, frequently of a height of six or seven feet, and the display rack of the above-mentioned patent, even when folded, required a package having a length corresponding to the overall height of the rack. This precluded shipment of such display racks by some package delivery services which have maximum package size limitations such as 108 inches combined length and girth.

SUMMARY OF THE INVENTION

It is the general object of the present invention to provide an upright revolvable display rack which can be disassembled, folded, and packed in a relatively flat package that is short as compared to the overall height of the display rack.

Another object of this invention is to provide an upright revolvable display rack in accordance with the foregoing object which can be made in various different heights without modification of the support structure for the display panels.

Still another object of this invention is to provide a revolvable display rack which is light in weight, economical to manufacture, and simple to erect and assemble.

Accordingly, the present invention provides a revolving display rack comprising a plurality of upright display panels mounted on a foldable frame structure for rotation about an upright post, the foldable frame structure including a plurality of upright frames mounted on hubs for relative movement between an expanded position in which the frames are angularly spaced apart around the hubs and a collapsed position in which adjacent ones of the frames are in sidewise adjacent relation for reception in a relatively flat package, the frames having channels on opposite sides arranged so that the channels on adjacent frames define oppositely facing pairs of channels when the frames are in their expanded position for slidably receiving a plurality of vertically elongated display panels, the foldable frame structure being short as compared to the overall height of the display panels and the display panels being each divided lengthwise into a pair of separate panel sections to allow packaging of the foldable frame structure and display panels in a relatively short and flat package. When erected, the adjacent ends of the panel sections are mounted in the channels on the foldable frame structure and the panel sections extend above and below the foldable frame structure and separate upper and lower panel connectors are provided for interconnecting the upper and lower panel sections at a level respectively above and below the foldable frame structure.

These, together with other objects, features, and advantages of the present invention will be more readily understood by reference to the following detailed description, when taken in connection with the accompanying drawings wherein:

FIG. 1 is a perspective view of a revolvable display rack embodying the present invention and with parts broken away to illustrate the features of construction.

FIG. 2 is a side elevational view of the display rack of FIG. 1;

FIG. 3

FIG. 3 is a top view of the display rack of FIG. 1;
FIG. 4 is a horizontal sectional view taken on the plane 4—4 of FIG. 3;

FIG. 5 is a horizontal sectional view taken on the plane 5—5 of FIG. 2.

FIG. 6 is a horizontal sectional view taken on the plane 5-5 of FIG. 2;

FIG. 7 is a vertical sectional view taken on the plane 7-7 of FIG. 4 and illustrating the unit on a larger scale and with parts of the panels broken away to shorten the overall view; and

FIG. 8 is an end view of the foldable frame structure for the display rack in a folded condition.

The revolvable display rack is adapted to stand on the floor and includes a base 10, a center post 11, at-

25 the floor and includes a base 10, a center post 11, attached to the base and extending upwardly therefrom, and a plurality of display panels 12, herein shown four in number, mounted in angularly spaced relation about the post for rotation relative thereto to permit the display panels and the articles carried thereon to be successively brought into view to an observer at one side of the display rack. The post 11 is rigidly secured to the base 10, but is made detachable therefrom to facilitate compact packaging, and the display panels 12 are 30 mounted on the posts by a foldable frame structure 13 which is foldable to a relatively flat condition for compact packaging. In order to reduce the overall length of the package required for the display rack, the display panels 12 are each divided into separate upper and 35 lower panel sections 12a and 12b respectively to allow reception of the panels in a package which is short as compared to the overall height of the display rack, and the frame structure 13 is also made short as compared to the overall height of the display rack, and preferably 40 45 no taller than the height of the individual panel sections 12a, 12b so that the foldable frame structure is also receivable in the same short relatively flat package with the panel sections 12a, 12b. The panel sections have their adjacent ends supported by the foldable frame 50 structure 13 and the upper and lower panel sections respectively extend above and below the foldable frame structure, and upper and lower panel connectors 14, 15 are provided for respectively interconnecting the upper and lower panel sections at levels above and below the 55 foldable frame structure. The lower panel connector means is rotatably supported on the center post 11 to support the panel sections against downward movement.

60 The foldable frame structure includes a hub means
21, 22 which is rotatably mounted on the post 11 and a
plurality of frames 23 which are mounted on the hub at
angularly spaced locations for movement between an
extended and a collapsed condition to enable reception
in a relatively flat package. As best shown in FIGS. 4
65 and 7, the upper hub member 21 includes a sleeve portion
21a which rotatably surrounds the post 11, and an
outwardly extending flange portion 21b. The lower hub
member 22 also includes a sleeve portion 22a that sur-

rounds the post 11 and an outwardly extending flange portion 22b. The sleeve portion 21a of the upper hub member closely surrounds the post 11 to radially support the upper end of the frame structure on the post and the sleeve portion 22a of the lower hub member is preferably spaced outwardly from the shaft to allow limited radial shifting movement of the hub for a purpose described fully hereinafter. The frames 23 each include upper and lower arms 24, 25 having laterally extending ends 24a, 25a extending through openings at equi-angularly spaced locations in the flange portions 21b, 22b of the hub members. The frames each have first and second upright channels 26, 27 secured to opposite sides of the upright and lower arms 24, 25 at locations spaced outwardly from the hubs for receiving the display panels 12. The channels 26 and 27 are arranged so that, when the frames are in their expanded condition shown in FIGS. 4 and 5, a channel 26 on one side of one frame opens toward the channel 27 on the other side of the adjacent frame to define an oppositely facing pair of channels which slidably receive the display panels. In the preferred embodiment illustrated, one of the channels 26 is spaced relatively closer to the hub than the other channel 27 and the upper and lower arms 24, 25 are angulated intermediate their ends and adjacent the channel 26 so that the inner portions 24b, 25b of the arms extend generally radially of the hub while the outer portions 24c, 25c extend generally parallel to a plane through an opposed pair of channels 26, 27 on adjacent frames, when the frames are in their expanded position shown in FIGS. 4 and 5. The portions 24c, 25c of the arms 24 and 25 are preferably spaced somewhat from their respective display panel 12 so as to not interfere with the mounting of the article mounting hooks 50 on the display panels, and the arms 24, 25 each have a laterally extending portion 24d, 25d at the outer ends which is connected to the outer channel 27. A handle is preferably provided on the arms outwardly of the outer channel 27 to facilitate turning of the display rack and, conveniently, the handle is in the form of an upright bar 28 which is connected to the outer ends of the arms 24, 25 at a location outwardly of the channels 27.

As previously described, the frames 23 are foldable relative to the hub to a relatively flat condition for compact packaging. One pair of frames 23 can be rigidly secured to the hubs 21, 22 as by welding indicated at 29 in FIGS. 4, 5, and 8, to maintain the hubs in axial spaced relation. The other pair of frames are swingable about the ends 24a, 25a of the arms 24, 25 to an expanded position extending outwardly at angularly spaced locations from the hub as shown in FIGS. 4 and 5, and a collapsed condition in which adjacent frames are disposed sidewise adjacent relation as shown in FIG. 8. The display panels 12, when inserted in the opposed pair of channels on adjacent frames, are effective to hold the frames in an expanded condition. However, in order to facilitate assembly of the display panels on the foldable frame structure, a means is advantageously provided for releasably locking the frames in their expanded condition. As shown in FIGS. 4, 7, and 8, circumferentially spaced portions 21c of the upper hub are bent upwardly and notched at 21d intermediate their ends, to receive the inner portions 24b, 25b of the upper and lower arms of the respective frames and releasably retain the frames in an expanded condition. The frames can be selectively folded by moving the arm portions 24b, 25b upwardly out of the notches 21d and

thereafter folding the frames alongside and adjacent frame as shown in FIG. 8.

The foldable frame structure is rotatably supported on the post at a selected level above the lower end of the post and, as best shown in FIG. 7, a thrust bearing 35 is disposed below the lower hub member 22. The thrust bearing is herein shown in the form of an anti-friction type having anti-friction bearing elements 35a interposed between washers 35b and 35c. The upper washer 35b underlies and engages the lower end of the foldable frame structure and a stop means, such as a pin 36 that extends through an opening in the post, engages the lower thrust washer to limit downward movement.

The upper and lower panel sections 12a, 12b have their adjacent ends slidably received in the opposed channels 26, 27 on adjacent frames with the ends of the panel sections in abutting relation to form a continuous display panel 12. The foldable frame structure is made short as compared to the overall height of the display rack and preferably no longer than the length of one of the display panels 12a, 12b so as to be receivable in a relatively short flat package with the foldable frame structure. The upper and lower panel sections respectively extend above and below the foldable frame structure 13 and the upper and lower panel connectors 14 and 15 respectively connect the upper and lower panel sections together at levels above and below the foldable frame structure. The lower panel connector member 15 is advantageously dimensioned to lie wholly inwardly of the display panels 12 and comprises a rigid frame structure 41 having a configuration corresponding to the shape of the space inwardly of the display panels, when the latter are in their erected condition as shown in FIGS. 3-6. An auxiliary hub 42 is secured to the frame structure 41 as by cross members 43 and the auxiliary hub 42 has a sleeve 42a that closely surrounds the post 11 to maintain the lower ends of the panel sections centered thereon. Studs 41a are attached to the frame structure 41 and extend outwardly from each side and the studs are adapted to extend through openings in the lower ends of the lower panel sections and to receive nuts 41b for rigidly securing the lower panel to the lower connector member. The panels 12 are slidably received in the opposed channels on the foldable frame structure and a thrust bearing means is provided for engaging the lower panel connector 15 to rotatably support the panels against downward movement. As shown in FIG. 7, the thrust bearing means includes a second thrust bearing 45 positioned to underlie and support the lower panel connector 15 on the post 11. The lower thrust bearing 45 also preferably is of the anti-friction type including anti-friction elements 45a and thrust plates 45b, 45c. Thrust plate 45b underlies the lower panel connector member 15 and thrust plate 45c is supported on the post as by a pin 46 that extends through an opening in the post. Thus, the upper thrust bearing 35 supports the weight of the foldable frame structure and the lower thrust bearing effectively supports the panels and the articles carried thereby.

The upper panel connector member 14 is also preferably disposed inwardly of the panels and includes a rigid frame structure 48 having a configuration corresponding to the opening inwardly of the panels as best shown in FIG. 3. The rigid frame 48 has outwardly extending studs 48a at each side which are adapted to extend through an opening in a corresponding one of the panels and to receive fastening nuts 45b to rigidly in-

terconnect the upper panel sections 12a. A bracket 49 is conveniently provided in the upper connector 14 for mounting a display sign (not shown) that extends above the display rack.

Various different brackets can be utilized for mounting articles on the display panels. In the preferred embodiment, display panels 12 are formed of perforated board having openings arranged in rows and columns and adapted to receive various different types of article support hooks, some of which are shown at 50 in FIGS. 2 and 4. The details of the article support hooks form no part of the present invention and further detailed description is deemed unnecessary.

From the foregoing it is felt that the construction and use of the display rack will be readily understood. As previously described, the post 11 is rigidly but detachably secured to the base 10 so that it can be removed to facilitate packaging of the post in the same plane as the base. Further, panels 12 can be removed and the foldable frame structure 13 can be collapsed to a generally flattened condition as shown in FIG. 8 for storage in a flat package. Further, display panels 12 are divided lengthwise into two endwise abutting sections so as to allow storage in a relatively short package and the foldable frame structure 13 is also made short as compared to the overall height of the display rack so as to be receivable in the same relatively short package with the display panels.

The rack of the present invention thus allows packaging of relatively tall rack, for example of the order of six or seven feet tall, in a relatively short flat package having a combined length and girth within the maximum package limits of 108 inches of some package carriers. Further, different height display racks can be made without changing the size of the foldable frame structure. In this regard it will be seen that different length panel sections can be utilized and that the thrust bearings 35 and 45 can be located at different positions along the posts, as by inserting the support pin 36, 38 through holes disposed at different locations along the post. Further, since the foldable frame and panels are adapted to be received in a package which is shorter as compared to the overall height of the display panel, it is possible to achieve a higher carton density, that is the package can be dimensioned in relation to the size of the panel sections and frame structure to provide a higher weight per unit of volume to further minimize shipping costs. In addition, since the foldable frame structure is short as compared to the overall height of the display rack, a saving on material is achieved which also reduces the cost of manufacturing the display rack as well as the shipping weight of the overall rack.

Although the display panels are divided lengthwise into two separate sections, and the frame structure is short as compared to the overall height of the display panels, the display panels are yet rigidly supported in angularly spaced relation by the foldable frame structure and the separate upper and lower panel connectors 14, 15, when the rack is erected. The foldable frame structure 13 engages the adjacent ends of the upper and lower panel sections to rigidly support the display panels in angularly spaced relation and the separate upper and lower panel connectors 14, 15 interconnect the panel sections at locations respectively above and below the foldable frame structure. The upper hub 21 and the auxiliary hub 42 closely surround the post to radially support the frame structure and panels on the post 11 while the lower hub 22 on the

foldable frame is radially spaced from the post 11 sufficient to prevent binding on the post. Since the display panels are slideable in the channels 26, 27 the foldable frame structure, the lower thrust bearing 45 effectively carries the weight of the display panels and the articles carried thereby.

The embodiments of the invention in which an exclusive property or privilege is claimed are defined as follows:

1. In an upright revolvable display rack including a base, a center post extending upwardly from the base, a foldable frame structure rotatably mounted on said post, and means on said post engaging said frame structure for rotatably supporting the frame structure at a selected level on the post, said frame structure including hub means, a plurality of frames each including upper and lower arms attached at one end to said hub means and first and second upright channels secured to opposite sides of the upper and lower arms of each frame at locations spaced outwardly from the hub means, the frames being mounted on the hub means for relative movement between an expanded position in which the frames are angularly spaced apart around the hub means and a collapsed position in which adjacent ones of the frames are in sidewise adjacent relation for reception in a relatively flat package, the upright channels on adjacent sides of adjacent frames defining oppositely facing pairs of channels when the frames are in their expanded position, and a plurality of vertically elongated display panels each having opposite side edges thereof slidably extending into a respective pair of oppositely facing channels on adjacent frames, the improvement comprising said frames each having a vertical length which is substantially shorter than said vertically elongated display panels and said display panels each comprise separate upper and lower panel sections having their adjacent ends in abutting relation at a location intermediate the upper and lower ends of channels on the frame structure, said upper and lower panel section respectively extending above and below the frame structure, a lower panel connector means separate from said foldable frame structure for interconnecting said lower panel sections at a level below said foldable frame structure, and upper panel connector means separate from said foldable frame structure for interconnecting said upper panel sections at a level above said foldable frame structure.

2. A display rack according to claim 1 wherein said frame structure has a vertical length no longer than the length of one of said panel sections.

3. A display rack according to claim 1 wherein said lower panel connector means includes a bottom hub member closely surrounding said post to be radially located thereby.

4. A display rack according to claim 3 wherein said hub means for said foldable frame structure includes upper and lower hub members respectively connected to said upper and lower means, said upper hub member on said foldable frame structure closely surrounding said post to be radially located thereby and said lower hub member on said foldable frame structure being radially spaced from said post to accommodate axial misalignment of the several hub members.

5. A display rack according to claim 1 wherein said means for rotatably supporting said frame structure includes a first thrust bearing means on the post engaging said hub means on the foldable frame structure, and a second thrust bearing means on the post engaging said

lower panel connector means for supporting the panels against downward movement.

6. A display rack according to claim 1 wherein said frames of said foldable frame structure each have a member spaced outwardly from the upright channels thereon and providing a handle for turning the rack.

7. In an upright revolvable display rack including a base, a center post extending upwardly from the base, a foldable frame structure rotatably mounted on said post, and means on said post engaging said frame structure for rotatably supporting the frame structure at a selected level on the post, said frame structure including hub means, a plurality of frames each including upper and lower arms attached at one end to said hub means and first and second upright channels secured to opposite sides of the upper and lower arms of each frame at locations spaced outwardly from the hub means, the frames being mounted on the hub means for relative movement between an expanded position in which the frames are angularly spaced apart around the hub means and a collapsed position in which adjacent ones of the frames are in sidewise adjacent relation for reception in a relatively flat package, the upright channels on adjacent sides of adjacent frames defining oppositely facing pairs of channels when the frames are in their expanded position, and a plurality of vertically elongated display panels each having opposite side edges thereof slidably extending into a respective pair of oppositely facing channels on adjacent frames, the improvement comprising said frames of said foldable frame structure, each have a vertical length which is substantially shorter than said vertically elongated display panels and said display panels each comprise separate upper and lower panel sections having their adjacent ends in abutting relation at a location intermediate the upper and lower ends of the foldable frame structure, at least the lower panel sections extending below

the lower end of the foldable frame structure, a lower panel connector means separate from said foldable frame structure for rigidly interconnecting said lower panel sections at a level below said foldable frame structure and thrust bearing means on said post engaging said lower panel connector means for supporting the panels against downward movement.

8. A display rack according to claim 7 wherein said lower panel connector means includes a bottom hub member closely surrounding said post to be radially located thereby.

9. A display rack according to claim 8 wherein said hub means for said foldable frame structure includes upper and lower hub members respectively connected to said upper and lower arms, said upper hub member on said foldable frame structure closely surrounding said post to be radially located thereby and said lower hub member on said foldable frame structure being radially spaced from said post to accommodate axial misalignment of the several hub members.

10. A display rack according to claim 9 wherein said upper panel sections extend above said foldable frame structure, and upper panel connector means separate from said foldable frame structure for interconnecting said upper panel sections at a level above said foldable frame structure.

11. A display rack according to claim 7 wherein said frames each have a member spaced outwardly from the upright channels thereon and providing a handle for turning the rack.

12. A display rack according to claim 7 wherein said upper panel sections extend above said foldable frame structure, and upper panel connector means separate from said foldable frame structure for interconnecting said upper panel sections at a level above said foldable frame structure.
